(57) **CLAIM**

The ornamental design for a mailbox tray insert, as shown and described.

DESCRIPTION

FIG. 1 is a top, front, left side perspective view of the mailbox tray insert of the present invention;

FIG. 2 is a front elevational view of the mailbox tray insert of FIG. 1, the rear view being a mirror image thereof;

FIG. 3 is a left side elevational view of the mailbox tray insert of FIG. 1;

FIG. 4 is a right side elevational view of the mailbox tray insert of FIG. 1;

FIG. 5 is a top plan view of the mailbox tray insert of FIG. 1; and,

FIG. 6 is a bottom plan view of the mailbox tray insert of FIG. 1.

The broken lines showing of a mailbox and post in FIG. 1 are for illustrative purposes only and form no part of the claimed design.
